ELECTROPNEUMATIC LOUD-SPEAKER

Joseph L. Fodor, South Norwalk, Conn.

Application January 29, 1946, Serial No. 644,148

13 Claims. (Cl. 179—108)

1

This invention relates to sound reproducing and amplifying means. It is applicable, for example, to the construction of loud speakers.

An object of the invention is to provide such a device, in which an air stream is modulated to generate sounds, with means for mounting the modulating means so that it will be extremely sensitive to vibratory impulses transmitted to it.

Another object of the invention is to provide air valve means of improved efficiency, comprising a plurality of slotted diaphragms separately open to the passage of air but adapted when superimposed to form an air seal in which the valve members, when the device is in use, will be spaced apart more uniformly and more nearly in parallel relation than in prior art devices thereby rendering all the slots of said diaphragms open for the passage of air and thus facilitating a maximum flow of air through the device.

Another object of the invention is to provide an improved assembly in which the closing movement of a delicately balanced movable diaphragm is progressively cushioned and undesired vibration due to striking together of the diaphragm members is minimized.

Another object of the invention is to provide such diaphragm mounting means with means facilitating adjustment of the relative positions of movable and fixed slotted valve members.

Another object of the invention is to provide simple, practical and efficient apparatus of the above mentioned kind.

Other objects of the invention will be in part obvious or in part pointed out hereinafter.

The invention accordingly consists in the features of construction, combinations of elements, arrangements of parts, and in the several steps and relation and order of each of said steps to one or more of the others thereof, all as will be pointed out in the following description, and the scope of the application of which will be indicated in the following claims.

The invention will best be understood if the following description is read in connection with the drawings, in which,

Figure 1 is a vertical section through a device embodying my invention;

Figure 1^a is a detail view showing the outer ends of the air outlet and inlet passages;

Figure 2 is a plan view of the device with the cover removed;

Figure 3 is a transverse sectional view taken through the voice coil and magnet assembly on the line 3—3 of Figure 1;

2

Figure 4 is a detail perspective view of the valve means employed; and

Figure 5 is a perspective view showing the assembled voice coil and pole pieces as a unit ready for insertion in the device;

Figure 6 is a plan view of the device, similar to Figure 2, but with the cover plate entirely removed; and Figure 7 is a cross sectional view taken on the line 7—7 of Figure 6.

10 In the embodiment of the invention as illustrated herein a hollow chamber is provided comprising the base member 10 and the cover 12 secured together as by screws 14 which extend through bores 16 provided at intervals around the marginal flange 18 of base member 10 and engage internally threaded bores provided in lugs 20 extending upwardly around the marginal flange 22 of casing cover 12.

20 Within the closure formed by the members 10 and 12 means are provided for vibrating a diaphragm or grid to generate sound impulses within the said chamber. The source of vibratory energy, as illustrated herein, comprises a voice coil and magnet assembly, the voice coil being 25 connected in a circuit through which may be supplied electrical impulses, which, for example, may have been translated into electrical energy from sound impulses delivered at a distance, as for example through a microphone connected in said circuit.

30 Preferably said assembly comprises a permanent magnet 24 to amplify the vibratory impulses delivered to an armature 26 which extends into the center of a voice coil 28, which may be wound on a spool-like support 30 having an aperture 32 extending axially through the hub of the spool and positioned between the pole pieces 34 and 36. As illustrated the spool-like support 30 comprises two complementary parts 40 having the interfitting open hub portions 30^a and 30^b (Figure 3).

35 The voice coil assembly is shown fixed in position between the parallel arms of magnet 24 by screws 31, which extend through a plate 33 overlying the assembly and are threadedly engaged in the upper surface of base 10. The magnet is held in place by a cross plate 25 which extends over the arms of the magnet and is held in place by screws 25^a which are threadedly engaged in base 10. As illustrated herein the respective ends, 96 and 98, of the voice coil winding 28 are led through base plate 10 into the space 100 situated below the voice coil and defined by the downwardly projecting base plate flanges 102 and 104, 55 and the removable cover plate 106, which is dis-

engageably secured to the said flanges as by means of screws 108. The said ends 96 and 98 are attached to a socket 110 which is adapted to receive the contacts of a plug connector (not shown) leading to a source of electric impulses, such for example as a microphone.

Preferably stops or positioning lugs 38 are provided extending upwardly from the base member 10 to aid in preventing unseating of magnet 24 in the event of shock to the device, such as might result if the device should be accidentally dropped or struck.

The armature 26 is attached at one end, as by screws 40, to an arm 42 the bifurcated end of which is pivotally mounted within the chamber on shaft 44, which is supported between the lugs 46 extending upwardly from base member 10.

On the under side of arm 42, adjacent its connection to said armature 26, a valve seat is provided adapted to receive a grid valve or diaphragm 48, which, as illustrated herein, is a disc-like member having a solid marginal portion 50 enclosing a central area comprising the alternate parallel slots 52 and intermediate web portions 54 reinforced by the circular unslotted portion or rib 56. Diaphragm 48 is supported by arm 42 so that its upper surface is spaced from the body of the arm permitting ready access of air within the chamber to the upper surface of said diaphragm.

The inner end of air outlet passage 60 is provided with a valve seat to receive a diaphragm 62, which may correspond exactly to member 48, the seats for members 48 and 62 being generally aligned but slightly offset horizontally so that the movable diaphragm member 48 may be superimposed upon fixed diaphragm 62, with the unslotted portions thereof including the marginal portion overlying and respectively covering all the slots or open portions of diaphragm 62 whereby an air seal will be provided when the surfaces of the said diaphragms are in contact.

It will thus be seen that the two diaphragm members 48 and 62 cooperate to form air valve means, and that although a stream of air passes freely through either diaphragm 48 or diaphragm 62 when said members are separated, said members coact to provide an air seal when movable member 48 is superimposed upon fixed member 62.

It will thus be seen that when armature 26 is vibrated, as by the alternate attractive and repulsive force of voice currents flowing through voice coil 28 and amplified by the permanent magnet 24, the vibratory movements of the armature 26 will be communicated to pivoted arm 42 and to diaphragm 48 causing diaphragm 48 to set up air impulses within said chamber and thereby modulating a stream of air flowing through said chamber. Such a stream of air may be introduced into the chamber, from any suitable source, such as a supply of compressed air, through the inlet passages 58, which are shown herein provided at spaced intervals around an air outlet passage or embouchure 60, which may be of a known kind desirably serving to amplify the sound impulses created within the chamber, and discharging into the chamber under arm 42.

Arm 42, which, it will be noted, extends substantially at right angles to air outlet passage 60, is rotated around a pivot which is spaced a considerable distance from valve member 48, and thus, in moving with armature 26 through the very narrow range of vibratory movement (a few thousandths of an inch) of armature 26 the arm

will maintain diaphragm or valve member 48 in a plane which is substantially parallel to the plane of valve member 62. Accordingly when the valve member 48 moves away from contact with valve member 62 all of the slots of both members will immediately be uncovered and open for the passage of air, thus permitting a maximum of air flow through the valve members, thereby facilitating maximum sound amplification.

The air inlets 58 deliver air into the chamber under said arm 42. During the operation of the device the bottom surface of valve member 48 and the surrounding portion of arm 42 is spaced from the upper surface of fixed valve member 62, which is substantially in the plane of the discharge ends of the air inlets, by a distance on the order of .003 of an inch. The incoming air impinges directly upon the portion of arm 42 surrounding the valve seat for diaphragm 48, and thus resists closing of the valve members and tends to revolve arm 42 in a clockwise direction around its pivot shaft 44. The resistance the incoming air streams exert against the closing movement of valve member 48 increases progressively as the valve closes, thus cushioning the closing of the valve members and preventing them from striking together with force sufficient to set up undesirable interfering vibrations.

30 The incoming air thus tends to "float" the arm 42 and this "floating" effect of arm 42 is further promoted by means of lever arm 64 which has a portion 63 adapted to extend between the bifurcated ends of arm 42, and is pivotally mounted 35 on shaft 44 on which member 42 is also mounted as has been explained. Portion 63 of lever arm 64 has a cross-bore 65 through which the shaft 44 extends the ends of the shaft also extending through bores in the bifurcated ends of arm 42 and being retained by screws 70 extending through lugs 46 respectively into recesses 72 in the ends respectively of shaft 44. The end of lever 64 which is on the opposite side of pivot shaft 44 from the diaphragm 48 is adjustably connected by link 66 to a pressure responsive member 68, which may comprise a collapsible means, such for example as a bellows of well known construction, mounted within the chamber, and in effect forming a wall portion thereof.

50 The pressure responsive member 68 tends to expand outwardly, and thus to increase the space within the chamber, when air is admitted to the chamber, thus pulling link 66 downwardly and causing lever 64 to be rotated in a clockwise direction.

55 In order to provide for accurately adjusting the position of diaphragm 48 with relation to diaphragm 62, and to align the closed portions of one diaphragm with the open portions of the 60 other diaphragm so that in superimposed position they will form an effective air seal, the arm 42 and the lever 64 are provided as separate members mounted on a common pivot shaft 44. Means are provided for interengaging arm 42 65 and lever 64 so that in effect they form together a unitary pivoted arm having pressure responsive means at one end, and the diaphragm 48 and the armature 26 adjacent the other end, the means illustrated comprising a pair of adjusting screws 74 extending through the internally threaded bores 75 extending horizontally through the spaced arms of member 42, respectively, said pressure screws 74 having pointed heads adapted to be received in conical recesses 76 provided in 70 the lateral edges respectively of the portion 63

of lever 64 projecting forwardly of its pivotal mounting on shaft 44. By means of the adjustment screws 74 the member 42 and part 63 may be secured together for rotation in unison around the center pivot shaft 44 and the position of member 42 may be adjusted laterally thus further facilitating the accurate positioning of diaphragm or valve members 48 and 62 relative to one another.

In order to increase the balanced, "floating" character of arm 42 means are provided for limiting the amplitude of vibration of arm 42. As illustrated herein this means comprises the springs 78 and 80, mounted on and around a rod 82, which extends through the vertically aligned bores 86 and 84 in arm 42 and in base member 10 respectively, and is threaded at its end to receive a nut 82^a serving to hold the rod in place and to adjust the tension of springs 78 and 80. Spring 78 is retained between the head 88 of rod 82, and the upper surface of arm 42 at 90. Similarly spring 80 is retained between the under surface of arm 42 and the top surface of portion 92 projecting upwardly from base member 10. Springs 78 and 80 thus serve to damp out vibrations of arm 42 which are greater than a predetermined amplitude and thus serve to limit the clockwise motion of arm 42 produced by the action of an inflowing air stream and the pressure responsive member 68.

It will be noted that the pivoted lever arm means which supports the movable valve or diaphragm member 48 extends substantially at right angles to both the air inlet and outlet passages and that because of this mounting and the "floating" effect achieved through the combined effect and coaction of the incoming air upon the under surface of arm 42 and the reaction thereto of pressure member 68, a delicate balancing of armature 26 is achieved rendering it highly responsive to actuation by the vibration inducing means.

Because of the improved balancing of arm 42 not only the armature 26 is rendered very susceptible to vibration creating impulses but the same is true with regard to movable valve or diaphragm 48 which is thus caused to set up sound waves modulating an air stream flowing through the chamber. And because the upper valve member 48 in moving toward and away from the lower valve member 62, maintains a substantially parallel relationship to said valve member 62 at all times due to its distance from pivot shaft 44, the slots throughout the entire area of both valve members are effectively open for the passage of air, except when the valve members are momentarily in superimposed contact with one another, when the flow of air through the outlet 60 will be entirely cut off.

It will thus be seen that there has been provided by this invention a method and apparatus in which the various objects hereinabove set forth together with many thoroughly practical advantages are successfully achieved. As various possible embodiments might be made of the mechanical features of the above invention and as the art herein described might be varied in various parts, all without departing from the scope of the invention, it is to be understood that all matter hereinbefore set forth or shown in the accompanying drawings is to be interpreted as illustrative and not in a limiting sense.

What I claim is:

1. In a sound reproducing and amplifying unit of the type having a movable valve member for modulating an air stream in accordance with

movement of a vibrating armature, a chamber closed except for air inlet and outlet passages, a first valve member extending across said outlet passage, an arm assembly pivotally supported within said chamber on a pivot located intermediate the ends of said assembly, a second valve member mounted on said assembly adjacent its end which is remote from said pivot and movable with said assembly into and away from a position of superimposition upon said first valve member, said valve members when separated each being adapted to pass an air stream but cooperating to form an air seal when superimposed, and means connected to said arm on the other side of the said pivot from said second valve member and adapted to regulate the angular position of said arm on its pivot, and to separate said valve members, when an air stream is passed through said chamber, thereby conditioning said arm to respond to vibrations of an armature connected to said arm.

2. In a device for translating electrical impulses into sound and amplifying them, a hollow chamber, closed except for having inlet means adapted for connection to a source of air under pressure, and an outlet, a first valve member fixed in position across said outlet, an arm pivotally disposed within said chamber on pivot means adjacent one end of said arm, and a second valve member mounted on said arm adjacent its other end for swinging movement therewith toward and away from said first valve member, said valve members being individually air permeable but adapted to form an air seal when brought together, an armature carried by said arm, and a voice coil positioned relatively to said armature to cause said armature to be vibrated by voice currents transmitted through said coil, pressure responsive means, and a pivoted lever associated with said pressure responsive means and with said pivoted arm whereby when compressed air is admitted to said chamber said lever is pivoted thereby pivoting said arm to move said second valve member away from said first valve member thereby opening said outlet and permitting a stream of air under pressure to flow through said chamber and rendering said second valve member responsive to vibrations of said armature induced by voice currents within said voice coil, to modulate said stream of air.

3. A device according to claim 2 in which there is provided means for adjusting said arm laterally to control the relative position of said first and second valve members.

4. A device according to claim 2 in which said arm and said lever are pivotally mounted on a common shaft, and there is provided means for interengaging said arm and said lever for movement in unison around said shaft.

5. A device according to claim 2 in which said arm and said lever are pivotally mounted on a common shaft, and there is provided means for interengaging said arm and said lever for movement in unison around said shaft, means for adjusting said arm and lever laterally, and means for adjusting the position of said arm angularly with respect to said lever to control the relative position of said valve members.

6. A device according to claim 2 in which the said air inlet is arranged to discharge into said chamber directly against the under side of the portion of said arm which is adjacent to said armature.

7. In a loud speaker adapted to reproduce and amplify sound, a chamber having an arm pivot-

ally mounted therein, a grid valve carried by said arm on one side of its said pivot, means connected to said arm on the other side of said pivot for balancing said arm when a stream of air is passing through said chamber, said chamber having an air outlet passage the inner end of which is aligned with said diaphragm, a plurality of air inlet passages disposed around said air outlet passage and adapted to deliver air into said chamber around the periphery of said grid valve into contact with said arm thereby cooperating with said balancing means for balancing said arm and swinging said grid valve with said arm away from the mouth of said air outlet passage when a stream of air is passing through said chamber, and thus together with said balancing means rendering said pivoted arm extremely sensitive to vibrations, and means for vibrating said arm thereby simultaneously vibrating said grid valve and causing modulation of an air stream passing through said chamber.

8. In a loud speaker adapted to reproduce and amplify sound, a chamber having an arm pivotally mounted therein, a grid valve carried by said arm on one side of its said pivot, means connected to said arm on the other side of said pivot for balancing said arm when a stream of air is passing through said chamber, said chamber having an air outlet passage the inner end of which is aligned with said grid valve, an air inlet passage surrounding said air outlet, and means for vibrating said arm including an armature projecting from said arm at a point remote from said pivot thereby simultaneously vibrating said grid valve and causing modulation of an air stream passing through said chamber.

9. In a device for translating electrical impulses into sound and amplifying them, a chamber, an air inlet passage communicating with said chamber, an air discharge passage leading

5

from said chamber, a stationary grid valve positioned across said discharge passage, an arm pivotally mounted in said chamber, a grid valve supported by said arm and movable with the arm from a closed position in which it is superimposed upon said stationary grid valve to a position in which it is separated from said stationary grid permitting air to be discharged through said stationary grid valve, said air inlet passage opening into said chamber directly beneath said pivoted arm whereby the incoming air tends to rotate said arm in a direction to separate the grid which is carried by said arm from said stationary grid.

10. A device as claimed in claim 9 in which the air inlet passage discharges under said pivoted arm at a point remote from said pivot.

11. A device as claimed in claim 9 in which said arm comprises two parts, means for interconnecting said parts for movement in unison and for adjusting the position of one of said parts laterally in relation to the other of said parts.

12. A device as claimed in claim 9 in which the said air inlet is disposed in the wall defining the said air discharge passage.

13. A device as claimed in claim 9 in which said arm has an armature mounted thereon and extending from it at a point removed from the pivot of said arm.
